DROP PLUG

Robert N. Miller, Rosemont, Pa., assignor to The Pennsylvania Railroad Company, Philadelphia, Pa., a corporation of Pennsylvania

Original application March 1, 1941, Serial No. 381,272. Divided and this application October 12, 1942, Serial No. 461,693

2 Claims. (Cl. 122—504.3)

This invention relates to safety plugs for steam boilers of the type comprising a hollow body component with a drop member normally sustained therein by a fusible bushing adapted to melt and release said member, under high temperature, for giving notice that the water in the boiler has lowered to an undesirable level. Drop members of the noted species are held in the body components by press-fitting or other assembly means, while relative "creeping" is normally prevented by axial compression of the fusible bushing.

The present application is a division from a prior one filed by the present applicant and William B. Miller under Serial No. 381,272, March 1, 1941, and allowed April 16, 1942; Patent No. 2,301,633.

The primary object of this invention is to provide a safety plug of the indicated type embodying refinements whereby the drop member is initially secured concentric with the axis of the body component bore and so retained until the intervening fusible bushing has sufficiently melted to permit the steam pressure in the boiler to blow said drop member directly out without any axial misalignment or tilting tendency conductive to "sticking," or leakage (passage) of steam into the fire-box, until the drop member is ejected.

Another object is the provision of an improved cold assembled safety plug in which the releasable member is positively retained in place against "creeping," until the moment when it is to be blown out.

Subsidiary objects, with ancillary advantages, will be understood as the nature of the invention is more fully disclosed, said invention consisting essentially in providing the safety plug body component with a converging bore having annular recesses at the outer and inner ends thereof and, incidentally to force fitment therein of a drop member with end surrounding recesses for confronting registration with the body component annular recesses, laterally expanding the intervening fusible sleeve ends into the said recesses of both members.

The accompanying sheet of illustrative drawing exemplifies a preferred embodiment of this invention, and wherein similar reference characters are applied to corresponding parts in all the views; while the concluding claims more particularly recite the features of novelty over the prior art.

In the drawing:

Fig. 1 is a vertical section through the body 55

component (or member) included in the illustrated typical embodiment of this invention.

Fig. 2 is a similar section including the fusible sleeve and drop plug, in initial assembly, and with fragmentary portions of appropriate securing means indicated by dot-and-dash lines.

Fig. 3 is a corresponding section illustrating the finished plug installed in a boiler crown sheet; and,

Fig. 4 is a perspective view of the drop plug.

In the following detailed explanation of this invention, specific terms will be employed for the sake of clarity, but it is to be understood such terms are used in a descriptive sense only and not for purposes of limitation, each said term being intended to include all technical equivalents which serve in a similar capacity to accomplish an analogous end.

Referring to the embodiment of this invention shown by Figs. 1-4 inclusive, the body component of the improved safety of drop plug is comprehensively designated by the numeral 1, said component embodying a machined cylindrical portion 2 having an inwardly converging bore 3, and an externally taper threaded part 4 for screw engagement in a correspondingly threaded aperture 5 provided for its reception in the boiler crown sheet 6.

The bore 3 is, preferably, formed with an inward taper of substantially three-quarters of an inch to the foot; while the bore of the taper-threaded part 4 includes an inner cylindrical counterbore 9, and an outer rectangular socket section 10, with the diagonally opposing corners angularly filleted at 11, as in the prior application hereinbefore identified.

Adapted for snug engagement in the plug bore 3 is a complementally tapered fusible material bushing 12 of even surrounding thickness and smooth circumferential finish, interiorly and exteriorly. This bushing 12, as shown to best advantage in Fig. 2, is of a longitudinal dimension substantially approximating that of the bore 3, and it preferably consists of an alloy containing eighty-five per cent lead with fifteen per cent tin; although any other suitable fusible alloy or mixture can be used.

The solid releasable closure member 13 is preferably of brass and a longitudinal taper complementary to that of the fusible bushing bore 14, but it is of fractionally greater diameter so that, when said member is initially inserted in said bore 14, it approximately occupies the position shown in Fig. 2, for a purpose later explained.

The bore 3 of the annular portion 2, it is to be

particularly noted, is of a substantially plain taper with a concentric annular recess 20 at the larger end and a similar spacially related one 21 at the lower end, whereby the intervening portion of the bore surface forms an inner continuous annular projection 22; while the releasable member or drop plug 13 is provided with end, or upper and lower reductions defining surrounding recesses 23, 24, respectively, for confronting registration with the body annular recesses 20, 21.

In assembling the plug 1 as described, it will be readily understood that the body portion 1 is placed over a suitable stationary die 17, Fig. 2, freely fitting the counter-bore 8 and spaced from the bottom of the bore of the portion 2, when the fusible bushing 12 is inserted in the bore 3 with its smaller end also seating on said die. The releasable solid member 13 is next deposited in the bore 14 of the bushing 12, whereupon a movable die 18, Fig. 2, is moved into engagement with the upper end 19 of the releasable member 13, and said member axially forced into position, in any conventional manner, towards the stationary die 17. Incidental to inward pressure movement of the member 13, the upper and lower ends of the bushing 12 will be laterally expanded and compressed into the respective grooves, defined by the spaced annular recesses 20, 21 and surrounding recesses 23, 24, with the intervening part intimately compressed between the projection 22 and confronting face 25 of the plug 13. Due to such press-fitting of the parts 1, 12 and 13 together, it will be obvious, said parts are firmly interlocked; while no "burr" will be formed either at the top or bottom of the bore 3,

or around the corresponding ends of the releasable plug 13.

Still further, it will be quite obvious that when low water in the boiler over the crown sheet 6 takes place, with resultant exposure of the top end 19 of the drop plug 13, the fusible bushing 12 will rapidly become overheated and melt, whereupon said plug will be blown out by the steam pressure, into the fire-box. Finally, due to the vertically spaced flange-like interengagement of the fusible sleeve 12 with the body portion 2 and ends 23, 24 of the drop plug 13, said plug is normally retained coaxially within the bore 3 until approaching the blow-out point, irrespective of any downward movement due to softening and progressive melting of the fusible sleeve 12 prior to its forced ejection into the fire-box.

Having thus described my invention, I claim:

1. In a drop plug, a body component including a cylindrical portion having an inwardly converging bore intermediate spaced annular recesses; a releasable closure member having end reductions defining surrounding recesses for confronting disposition relative to the annular recesses in the cylindrical portion bore; and a fusible material plain bushing intermediate the cylindrical portion bore and the closure member with its ends laterally expanded into the intervals jointly defined by the annular recesses in the body and closure.

2. The combination of claim 1 wherein the body component annular recesses, and the closure member surrounding recesses, are of rectangular cross-section and concentrically-related.

ROBERT N. MILLER.
